ASSIGNORS TO W. G. CORNELL COMPANY, OF NEW YORK, N. Y., A CORPORATION OF
NEW YORK.

SUPERVISORY SYSTEM FOR SPRINKLER-VALVES.

1,153,573.

Specification of Letters Patent. Patented Sept. 14, 1915.

Application filed February 6, 1915. Serial No. 6,441.

To all whom it may concern:

Be it known that we, WILLIAM A. ROGERS and MCREA PARKER, citizens of the United States, residing at Washington, in the District of Columbia, have invented certain new and useful Improvements in Supervisory Systems for Sprinkler-Valves, of which the following is a specification.

This invention relates to improvements in protective or supervisory apparatus for the valves of water service or sprinkler systems.

In systems of this character it is the usual practice to provide shut-off valves at various points in the mains leading to different parts of a building, and safety requires that such valves be always open and the system in working condition. Fire underwriters recognize the possibility of these valves being inadvertently left closed, or being closed or tampered with by unauthorized persons, and many of them require that means be provided for ascertaining with certainty at all times the condition of the system in this respect.

It is the main object of the present invention, therefore, to provide means for indicating at a central office the condition of every valve in the system, and for sounding an alarm in case any valve is moved from its normal position or the circuit wires broken or cut.

Another object is to safeguard such a system against accident by providing means for indicating to the attendant that the source of current has failed, if such a contingency should arise.

To this end, we have devised a system operating on a normally closed circuit, and employing an improved combined relay and annunciator having a target movable by gravity to abnormal position. We have also provided simple, rugged and efficient circuit controlling devices located at the valve to be protected, and governing the operation of said relays.

In order that the invention may be readily understood, reference is had to the accompanying drawings, forming a part of this specification, and in which,

Figure 1 is a side elevation of part of a gate valve showing our invention applied thereto; Fig. 2 is a fragmentary central section substantially on the line 2—2 of Fig. 1,

parts being omitted; Fig. 3 is an enlarged plan view of the contact supporting plate; Fig. 4 is a longitudinal section thereof, substantially on the line 4—4 of Fig. 3; Fig. 5 is a transverse section thereof on the line 5—5 of Fig. 3, parts being in elevation; Fig. 6 is a transverse section on the line 6—6 of Fig. 1; Fig. 7 is a transverse section on the line 7—7 of Fig. 1; Fig. 8 is a plan view of the improved combination relay and annunciator which we employ; Fig. 9 is an edge view thereof; and, Fig. 10 is a diagram of the circuit connections employed in our improved system.

Referring to the drawings in detail, 1 designates a portion of the casing of a gate valve such as is usually employed in connection with sprinkler systems.

2 indicates the usual yoke, and 3 the valve stem, the outer end of which is threaded as indicated at 4, and works through the threaded hub of a hand wheel 5, by means of which the valve may be opened and closed.

In order to provide the necessary circuit controlling elements, we preferably form a dove-tailed slot 6 along one side of the valve stem, such slot extending somewhat beyond the termination of the threads. Into such slot is driven a strip 7^a of insulating material, such as fiber or hard rubber, such strip being forced inward to the inner limit of 85 the slot and terminating a suitable distance from the end of the stem. A filler strip 7, of brass or the like, is then driven in so as to extend from the end of the hard rubber strip to the end of the valve stem. This brass 90 strip and the greater portion of the strip of insulation is of such thickness as to fill the slot to the level of the base of the threads, but at the inner end the insulating strip is brought gradually up flush with the surface 95 of the smooth portion of the stem, as indicated at 7^b in Figs. 1, 2, and 7. The result of this construction is that there is a strip of insulation of definite length embedded in and surrounded by the metal of the valve 100 stem. Adapted to ride upon this strip of insulation is a pair of contact fingers which will now be described. These fingers are preferably supported in a plate 8 of insulating material, secured to the yoke 2. The 105 contacts may conveniently be formed of a pair of cylindrical barrels 9 and 10, passing through holes in the plate 8 and secured

to the fingers.

therein by means of set screws 11. Contact fingers proper, 15 and 16 are resiliently mounted in the ends of the barrels 9 and 10, respectively, each of such fingers being carried by a plunger 13 fitting within a cylindrical pocket in the respective barrel and urged outward by means of a helical spring 14. Each contact finger, such as 15, is of relatively thin, flat formation and slides freely in a slot 12 formed in the end of each barrel. It will thus be seen that the contact fingers 15 and 16 are caused to bear against the valve stem with a resilient pressure, and are adapted to ride along the groove 6, as the valve stem travels back and forth. Electrical connections are made with the contacts 9 and 10 by means of binding screws 17 and 18, respectively.

Referring to Figs. 8 and 9, the improved combination relay and annunciator will now be described. This instrument consists of a suitable base 20 of magnetic material, having at one end a portion 21 extending at right angles to the base. To this flange 21 are secured a pair of electromagnets 22 and 23, having cores 22^a and 23^a, respectively. It will be seen that these cores are in direct contact with the flange 21.

An armature 24 extends in front of both cores or pole pieces 22^a and 23^a, and is pivotally supported by means of a leaf spring 25, upon a lug 26 formed integral with the base. A second leaf spring 27 is secured to the armature, and a set screw 28 bears against this spring in such a manner as to regulate its tension. One of the springs 25 or 27 is extended to form a resilient contact 29, adapted to engage the point of a contact screw 30, which is adjustably carried in a second lug 31, supported by the base 20. The point of this contact screw 30 is preferably made of platinum or the like, to prevent corrosion. Binding screws are provided by which circuit connections with the armature 24 and contact screw 30 can be independently made. It will be understood that the armature 24, when the magnets 22 and 23 are deenergized, normally rests in such a position as to establish contact between the spring 29 and screw 30, being urged to such position by the spring 25. When, however, either magnet 22 or 23 is energized, the armature is drawn toward the magnets and the connection between the spring 29 and screw 30 is broken.

Secured to the flange 21 and projecting forwardly therefrom is a bracket 32, formed of non-magnetic material. Pivoted at 36 to the end of this bracket is a permanently magnetized steel bar 35, carrying at one end a light vane, or target 37, serving as an indicator. Wings 33 and 34 extend from each side of the bracket 32 and form stops to engage the bar 35 so as to limit its movement about the pivot 36. A counter-weight

38, preferably of non-magnetic material, is secured to one end of the bar 35 in such a position as to extend to one side thereof, whereby the bar and target are biased to a definite position. This position is shown in full lines in Fig. 8 and it is obvious that the target will be shifted by gravity to such position, if free to move.

In practice, there will be a number of instruments such as illustrated in Figs. 8 and 9, mounted in a suitable cabinet at a central point, after the manner of an ordinary annunciator. Associated with this cabinet will be provided an electric bell or gong of any suitable character. A pair of wires 80 will extend from each relay to some one of the valves which it is desired to protect, all of said relays and the gong being operated from a common battery.

Fig. 10 diagrammatically represents an installation in which two relays are employed, the same being electrically connected with two valve stations. The relays are indicated in their entirety by the reference letters *a* and *b*, and the respective valve stations by the letters A and B.

40 designates a battery or other suitable source of current, one side of which is connected by means of a wire 39 with the pipe system, or other common return. A gong 48 is connected between the wire 39 and a common wire 41, which extends to all of the relays and is connected to the contact screw 30 of each of them. A wire 42 extends from the other side of the battery to all of the relays, and is connected to one end of the winding of each of the magnet coils 22 and 23 thereof, said coils being so wound or connected as to generate magnetic fluxes in opposite directions. Wires 46 and 47 extend from the other side of said magnet coils, respectively, to contacts 9 and 10, mounted on the valve at station A, while similar wires 46' and 47' extend to like contacts 9', 10', on the valve at station B, etc. It will therefore be apparent that each of the magnet coils 22, 23, of each relay is in an independent circuit, one side of such circuit being formed by one of the wires, such as 46, and the other side being completed through the ground connection or other common return.

The valve at station A in Fig. 10 is indicated as open, or in normal position. In such position, the contact 9 rests upon the valve stem 3, while the contact 10 rests upon the strip of insulation. Current therefore flows normally from battery 40, through wire 42, wire 44, electromagnet 22, wire 46, contact 9, and valve stem 3 to ground, whence the circuit is completed through the wire 39 to the other side of the battery. The magnet 22 is therefore energized and the armature 24 of relay *a* attracted, thus holding the gong circuit open at 30. The energization of magnet 22 is in such a direction as to

cause the polarized bar 35 and target 37 to assume the position shown in full lines at *a* in Fig. 10, or in dotted lines in Fig. 8. The single magnet winding 22, therefore, serves both to control the armature 24 and the annunciator target 37.

In the upper part of Fig. 10, the relay *b* and valve station B are shown in the condition they assume when the valve has been

- 10 partially closed. Under such conditions, the valve stem occupies a position such as shown in Fig. 2, with both contacts 9 and 10 resting upon the insulated strip. The first movement of the valve stem from the normal position, interrupting the circuit at contact 9, deenergized magnet winding 22, and the instant this occurred, the target 37 was moved over by gravity to the position shown. Both magnet windings of relay *b* 15 being therefore deenergized, the armature 24 is thrown by its spring against the contact screw 30, thus closing the gong circuit from battery 40, through wire 41, and wires 45' and 42. The gong therefore continues 20 to ring so long as any valve remains in an intermediate or partially closed position. When, however, the valve has been entirely closed, as is sometimes necessary for the purposes of testing or repair, the contact 10 25 rests upon the metal strip 7, thus closing the circuit through magnet 23, and causing the gong circuit to be opened by the movement of the armature 24 away from the contact screw 30. The energization of magnet 23 30 is in such direction as to tend to move the polarized bar 35 and target 37 to the position shown in full lines in Fig. 8, but, as explained above, they have already been swung to such position by gravity, and coil 23 35 serves only to maintain them in this position. This indicates to the attendant that the valve is closed. The particular object, however, of the counterweight is to cause the target to move to closed or "defect" position in case of the failure of the source of 40 current, or a break in the circuit wires. Should the battery fail, both windings of all of the relays would, of course, become deenergized, but the gong would not be 45 sounded, owing to lack of current. However, the targets on the relays would all move to the right, as shown in full lines in Fig. 8, thus indicating to the attendant that there was some defect in the system. 50 If, on the other hand, one or both of the wires 46 or 47, leading to any valve station, should become broken, the armature of the corresponding relay would be released, thus closing the gong circuit and giving an alarm, 55 while at the same time, the target of that particular relay would be moved by gravity to its "defect" position, thus indicating to the attendant which particular valve circuit was out of order. 60

65 It will thus be seen that we have provided

a supervisory system operating upon the closed circuit principle, thereby giving indication not only of the position of the valves, but also of the condition of the various circuits and source of current, and it is thought 70 that the many advantages of such a system, as well as our improved combined relay and annunciator, will be readily appreciated without further discussion.

What we claim is:

1. The combination with a valve, of electrically operated means for indicating whether the same is open or closed, and means for sounding an alarm when said valve occupies an intermediate position. 80

2. The combination with a plurality of valves, of electrically operated means for indicating at a central station whether each valve is open or closed, and means for sounding an alarm when any of said valves is 85 moved to an intermediate position.

3. In a supervisory system for valves, the combination with a valve stem, of circuit controlling devices operated thereby, a relay having magnet windings governed by said circuit controlling devices, an alarm circuit controlled by said relay, and an indicating device associated with said relay independent of said alarm circuit and responsive to the presence or absence of current in the 90 windings thereof.

4. In a supervisory system for valves, a relay, a valve, and means governed by said valve for maintaining said relay energized so long as said valve remains in either its open or closed position, and for causing the deenergization of said relay when said valve occupies an intermediate position, and an alarm controlled by said relay. 100

5. In a supervisory system for valves, an alarm, a circuit therefor, a relay serving when energized to maintain said circuit open, a valve, and means governed by said valve for maintaining said relay energized so long as said valve remains in either its open or closed position, and for causing the deenergization of said relay when the valve occupies an intermediate position, and means operating, upon the deenergization of said relay, to close said alarm circuit. 110

6. In a supervisory system for valves, the combination with an alarm, of a relay having an armature controlling the same, said relay being provided with two independent windings, and said armature being operated by either winding, a valve, and means associated therewith for energizing one only of said windings when the valve is open, and the other only of said windings when the valve is closed. 120

7. In a system of the character described, the combination with a relay, of circuit controlling devices therefor, said relay having a pair of separate electro-magnetic bobbins, and a common armature operated in the 130

- same direction by either of said bobbins, an alarm circuit controlled by said armature, and an indicating device associated with said relay, said device being governed in its 5 position by the energization of said bobbins, and independent electrical connections between said bobbins and said circuit controlling devices.
8. In a system of the character described, 10 the combination with an alarm, of a relay wholly controlling the same, said relay having two independent windings, and an indicator capable of occupying either of two positions, and biased toward one position, 15 said indicator being selectively shifted by the energization of one or the other of said windings.
9. In a system of the character described, 20 the combination with a valve, of an electro-magnetic annunciator capable of giving two distinct indications, a source of current, a pair of circuits, including said source, extending from said valve to said annunciator and controlling the latter, and means 25 operated by the movement of said valve to open or closed position for respectively closing one or the other of said circuits, and thus producing in said annunciator one or the other of said distinct indications corresponding with the position of the valve.
10. In a system of the character described, 30 the combination with an alarm, of a relay having an armature controlling the same, said relay having two independent windings arranged to generate magnetic fluxes in opposite directions, and an indicator independent of said armature capable of occupying either of two positions and biased toward one position, said indicator being selectively 40 shifted by the flux set up by said windings.
11. In a system of the character described, 45 a relay having two independent windings arranged to generate magnetic fluxes in opposite directions, an armature movable in the same direction by the energization of either winding, an alarm controlled by said armature, and a polarized indicator associated with said windings and movable in re-
- 50 sponse to the direction of the flux respectively set up thereby.
12. In a system of the character described, 55 the combination with electro-magnetic apparatus, of a pair of circuits for controlling the same, said apparatus having windings part of which are included in each of said circuits, an indicator operated by said windings and movable one way or the other by the selective energization of said circuits, an independent alarm circuit, and an armature governing the same, said armature 60 being also operated by said windings, and movable in the same direction by the energization of either of said control circuits.
13. In a system of the character described, 65 electro-magnetic apparatus having windings, a part of said windings being arranged to generate magnetic flux in one direction and another part in the opposite direction, a pair of control circuits in which said parts of the windings are respectively included, a polarized indicator associated with said windings and movable in response to the direction of the flux set up thereby upon the selective energization of said circuits, an alarm circuit, and an armature also associated with 70 the windings and governing the said alarm circuit, said armature being movable in the same direction by the energization of either of said control circuits.
14. In a supervisory system for valves, the 75 combination with a non-rotary valve stem, of a strip of insulating material carried thereby, a pair of contact fingers adapted to rest at times on said strip and at other times on the stem itself at each end of said strip, 80 a relay, circuit connections between said relay and said contact fingers, and a signal controlled by said relay.
